(57) **CLAIM**

The ornamental design for a socket cover, as shown and described.

DESCRIPTION

FIG. 1 is a first perspective view of a socket cover showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of another state of the socket cover thereof.

The broken lines shown in the drawings depict portions of the socket cover that form no part of the claimed design.

1 Claim, 9 Drawing Sheets
